UNITED STATES PATENT OFFICE.

THOMAS H. LOGAN, OF LOWELL, MASSACHUSETTS.

DEVICE FOR CONNECTING PICKING-STRAPS TO THE PICKING-STICKS OF LOOMS.

SPECIFICATION forming part of Letters Patent No. 325,350, dated September 1, 1885.

Application filed January 26, 1885. (No model.)

To all whom it may concern:

Be it known that I, THOMAS H. LOGAN, a citizen of the United States, residing at Lowell, in the county of Middlesex and Commonwealth 5 of Massachusetts, have invented certain new and useful Improvements in Devices for Connecting Picking-Straps to the Picking-Sticks of Looms, of which the following is a specification.

10 My invention relates to devices for connecting picking-straps to the picking-sticks of looms; and it consists in the hereinafter-described devices and combinations.

In the accompanying drawings, Figure 1 is 15 an isometric view of my invention attached to a portion of a picking-stick, the loop being swung outward from the stick; Fig. 2, a side elevation of a portion of a picking-stick to which my invention is attached, the loop and 20 block and a part of the picking-stick being in central vertical transverse section, the loop being in the same position with reference to the stick as in Fig. 1; Fig. 3, a side elevation of a part of the picking-stick, showing the block 25 attached thereto and the picking-loop pivoted to said block, the block being partly in section and the loop being in central vertical transverse section, the lower end only of the loop being in contact with the stick; Fig. 4, 30 the same as Fig. 3, except that in Fig. 4 the straight part of the inner side of the loop is in contact with the stick from end to end of said loop; Fig. 5, a front elevation of a part of the frame of a loom and a part of the lay-beam and lay-shaft provided with the bed-piece, the picking-stick, its rocker, the picking-strap provided with a loop, and my invention 35 secured to said picking-stick; Fig. 6, an elevation of the outer side of a part of a picking-stick and the upper part of the block attached thereto, showing the means of adjusting said block.

The frame A, lay-beam B, provided with the guide-slots b, lay-shaft C, rocker-bed D, 45 rocker E, picking-stick P, picking-strap S, and its loop s, are all of the usual construction and operation.

The loop s of the picking-strap S surrounds 50 the picking-stick, and is commonly held at the desired height by a holding-loop of leather, one end of which is passed up through the

loop s, the ends of said holding-loop being secured to the picking-stick by a screw driven through said ends and into said stick above the loop s.

To vary the force of the blow of the picker, which is attached to the upper end of the picking-stick, as is well known, it is necessary to hold the loop s at a greater or less height above the rocker E, (which serves as the fulcrum of said stick,) and the picking-stick (commonly of ash) is provided with several holes, placed one above the other at intervals of about half an inch, into one or another of which said screw is driven, according to the height at 65 which it is desired to hold the picking-strap; but these holes are likely to become worn and allow the screw to become loose after several removals of the same. A finer adjustment than can be obtained by the screw-holes above 70 mentioned is sometimes desirable, and to put the holes nearer together would increase the tendency of the stick to split when struck by the shuttle. The ordinary loop which holds up the picking-strap is sharp-cornered, so 75 that it and the picking-strap loop wear rapidly upon each other. It is desirable, moreover, to have the picking-stick yield somewhat when the picker is struck by the shuttle, so that the filling or cop of the shuttle may not 80 be jarred off the shuttle-spindle by the suddenness with which the shuttle is brought to a stop. The attempt has been made to remedy these defects by the use of a holding-loop 85 of round spring-wire; but such loops are apt to be soon broken, and they cannot well be made with sufficient elasticity.

Instead of the holding-loops above referred to, I use a stiff metallic loop, F, having a solid shank, f, at its upper end, which shank 90 is placed between ears h h, cast or otherwise secured on a block, H, (supported on the picking-stick, as hereinafter described,) and is held between said ears by a horizontal pivot, I, which runs through said ears and through 95 a hole, f', in said shank. The pivot I is cylindrical in cross-section; but the hole or slot f' in the shank is oblong horizontally, which allows of the shank being moved toward or away from the block H and picking-stick. 100 The inner side (or side toward the picking-stick) of the shank f is provided with a re-

cess, f'' , of suitable size and shape, below the pivot I, and in this recess is placed a spring, K, preferably a spiral spring, which spring is compressed between the bottom of said recess 5 and the block H, and tends to throw the loop proper out from the picking-stick; but the motion of the loop away from the picking-stick, caused by the expansion of said spring, is limited by the upper end of the shank, 10 which is prolonged upward from its pivot I striking against the block H. Just before the picker is struck by the shuttle the picking-stick is inclined outward as far as it can go without compressing the spring K, and the 15 blow of the shuttle causes the picking-stick to swing still farther outward, compressing the spring K, and bringing the lower end of the loop F against the outside of the picking-stick, as shown in Fig. 3, and finally bringing 20 the picking-stick in contact with the straight inner side of said loop F along the whole length of said loop, as shown in Fig. 4.

Making the slot f' oblong horizontally allows of the straight inner edge of the loop F 25 lying against the picking-stick.

The construction above described causes the picking-stick to yield somewhat and causes the shuttle to be stopped gradually and acts as a "filling-check,"—that is, it prevents 30 the filling from being knocked off the spindle of the shuttle by the sudden stopping of the shuttle.

The block H is a little wider than the thickness of the picking-stick, and has on its inner 35 face, on one or both sides, ribs h' , which lie along the front and rear faces of the picking-stick, and is held in contact with said stick by a wood screw, J, which passes into the picking-stick through a horizontal slot, h^2 , 40 through said block. The outer face of the block H is provided with two or more countersunk enlargements, $h^3 h^3$, (see Figs. 1, 2, and 6,) of sufficient size to receive and fit the head j of the wood screw J, the shank j' of 45 which has, just below the head, a diameter equal to the width of the slot h^2 between the enlargements $h^3 h^3$. The countersunk enlargements are intended to be about half as far

apart as the holes which ordinarily receive the screws of the holding-loop, so that by 50 loosening the screw J until the head j is clear of the block, said block may be adjusted up or down on the picking-stick by intervals one-half as great as usual without entirely removing the screw from the stick and block. The 55 screw J being then tightened, the block is held in the desired position.

I claim as my invention—

1. The combination of the block adapted to be attached to a picking-stick and provided 60 with ears, a loop having a shank pivoted to said ears between the same, and a spring placed between said block and said shank, as and for the purpose specified.

2. The combination of the block adapted to 65 be attached to a picking-stick and provided with ears, a loop having a shank pivoted to said ears between the same and provided with a recess and a spiral spring placed within 70 said recess and compressed between the bottom of said recess and said block, as and for the purpose specified.

3. The combination of the block adapted to 75 be attached to a picking-stick and provided with ears, a loop having a shank pivoted to said ears between the same, and a spring placed between said loop and its pivot and compressed between said shank and said block, 80 said shank extending beyond said pivot on the opposite side of said pivot from said spring 85 to limit the motion of said loop around said pivot, as and for the purpose specified.

4. The combination of the block adapted to 90 be attached to a picking-stick provided with ears having holes, a loop provided with a shank having a pivot-hole oblong horizontally, a cylindrical pivot passing through the holes in said ears and the pivot-hole in said shank, and a spring placed between said block and said shank, as and for the purpose specified.

THOMAS H. LOGAN.
